UNITED STATES PATENT OFFICE.

SAMUEL STANICK, OF MARLBORO, MASSACHUSETTS, ASSIGNOR TO UNITED SHOE MACHINERY CORPORATION, OF PATERSON, NEW JERSEY, A CORPORATION OF NEW JERSEY.

METHOD OF AND MEANS FOR ATTACHING ELASTIC HEELS TO BOOTS OR SHOES.

Application filed June 24, 1921. Serial No. 480,056.

To all whom it may concern:

Be it known that I, SAMUEL STANICK, a citizen of Germany, residing at Marlboro, in the county of Middlesex and State of Massachusetts, have invented certain Improvements in Methods of and Means for Attaching Elastic Heels to Boots or Shoes, of which the following description, in connection with the accompanying drawings, is a specification, like reference characters on the drawings indicating like parts in the several figures.

This invention relates to methods of and means for attaching elastic heels to boots or shoes.

Heels of this class are commonly composed of rubber or a composition containing rubber, and in the process of their manufacture are vulcanized in a mold which determines their size and shape. Such heels usually have embedded in them washers through which the nails for attaching the heel to the shoe are to be driven, the heads of the nails being seated upon the washers. In the process of manufacture of the heel, washers are placed upon pins in the mold above referred to, and the mass of rubber composition is filled in around them and vulcanized. Inasmuch as the pins occupy fixed positions in the mold cavity, it might be expected that the positions of the washers in all heels from a given mold would be the same, and this is nearly enough true to meet the requirements of the method of attaching the heels which was formerly generally practised, namely by inserting the attaching nails and driving them by hand.

In recent years heeling machinery has been developed for attaching elastic heels and, with the tremendous increase in the use of such heels, its employment has become a commercial necessity. It is frequently found that the location of the washers in rubber and like heels is not accurate enough to secure sufficiently exact register with the holes in the nailing die of the heeling machine to ensure that the nails shall pass through the washers with certainty. The inaccuracy and variation in the location of the washers in the heels may be due to a variety of causes, such as shrinkage or unbalanced stresses in

the rubber causing the washers to shift after the heel is removed from the mold, bent washer pins, pins not identically located in different molds, etc. Another reason for failure to secure accurate register of the washers with the holes in the nailing die lies in the fact that the more or less yielding material in the elastic heel is distorted by the pressure of the heeling machine so that the washers are shifted from their normal relation to each other into uncertain positions.

Furthermore, it is very common to provide suction cups or cavities in the tread face of a rubber heel, for the purpose of ornamentation and to prevent slipping upon wet surfaces, and these cavities are usually co-axial with the washers. The uncertainty of the nails entering the washers properly is aggravated in the case of such heels by the fact that a considerable blank space exists between the face of the nailing die of the heeling machine and the bottom of the cavity where the attaching nail really begins to enter the substance of the heel. The nail is not guided in this space and, not infrequently, swings to one side or the other sufficiently so that it enters the heel substance at the bottom of the cavity at an inclination and is deflected away from the hole in the washer, sometimes even missing the washer entirely.

It is the object of the present invention to overcome the various difficulties above enumerated and to provide a method and apparatus, by the use of which, elastic heels may be attached with speed, accuracy, and uniformity, without loss of time or waste of material.

To this end the invention consists, in one aspect, in an improved method of attaching elastic heels containing washers, characterized by the steps of first forcing the washers, which may not be identically located in different heels, to predetermined, fixed locations, and then driving heel attaching fastenings through the holes of the washers thus positioned. As a more specific development of the invention when applied to a heel having cavities in its tread face, the improved method comprises the accurate posi-

tioning of the washers in predetermined locations by the engagement of the wall of the cavity by a positioning tool or instrument, through the agency of which that portion 5 of the heel body which contains the washer is moved, if necessary, into an exact, predetermined position. By this method not only are misplaced or displaced washers forced into their proper positions, but displacement 10 of the washers due to distortion of the heel by the pressure employed in the attaching operation is prevented. While this novel method may be practised with the aid of a variety of tools or implements, a feature of 15 the present invention includes the provision of improved means particularly adapted to facilitate the practice of the method and, in the embodiment illustrated herein, comprising a pressure applying member having 20 suitably disposed projections arranged to engage portions of the heel in the region of the washers and position the washers transversely in predetermined relative locations.

Preferably, the washer positioning projections are carried by the nailing die of a heel- 25 ing machine which thus constitutes the pressure applying member and, besides positioning the washer carrying portions of the heel, has the function of guiding the at- 30 taching nails continuously to the point where they actually enter the heel.

Various other features and advantages of the invention will be apparent from reading the following detailed description of a spe- 35 cific embodiment thereof in connection with the accompanying drawings, in which

Figure 1 illustrates a rubber heel applied to a leather or leatherboard base, ready to be attached to a shoe;

Fig. 2 shows the upper portion of a well known type of heeling machine provided with a nailing die embodying the present invention;

Fig. 3 is an enlarged sectional view showing the rubber heel just beginning to engage the pressure applying portion of the nailing die; and

Fig. 4 is a view partly in perspective and partly in section showing the heel under pressure, with the washers positioned and the attaching nails driven.

Referring now to the drawings, 10 indicates a well known type of rubber heel which is in extensive commercial use. The heel 10 is shown in Fig. 1 as applied to a heel base 12 consisting of one or more lifts of leather, leatherboard or like material.

Suction cups or cavities 14, surrounded by elevations 16 are formed in the tread face 60 of the heel and are co-axial with the holes 18 which are formed in the heel by the pins upon which the washers 20 are supported in the heel mold while the heel is being formed and vulcanized. For reasons already ex- 65 plained, the locations of the cavities, and

particularly of the washers 20, with relation to each other, are not always identical in the different heels of a given lot.

Referring to Fig. 2, 22 indicates the driver head and 24 the nail drivers of a well known type of heeling machine. The shoe 26 to be heeled is supported upon a jack 28 by which it may be raised to press a heel positioned on the heel seat of the shoe against the under side of the nailing die 30. 75

Figs. 3 and 4 show on an enlarged scale a plate 32 which may be secured to the under side of the nailing die 30 as a matter of manufacturing convenience, or the lower face of the nailing die, for the purposes of 80 the present invention, might equally well have the conformation illustrated upon the lower face of the plate 32. As shown, the nail holes in the member 32 are of the same size as, and are placed in exact alinement 85 with, the nail and driver guiding holes 36 in the major portion of the die 30. Each of the holes 34 is surrounded by a projection 38 which is of substantially the same size and shape as one of the cavities 14 in 90 the tread face of the heel to be attached. The location of the projections 38 in relation to each other, is, of course, predetermined and, in the illustrated machine, fixed. The position of the holes 34 is identical with the intended position of the holes 18 in the heel, but Fig. 3 illustrates a condition which not infrequently exists, viz., the holes 18 are not spaced exactly the same as the holes 34 and, therefore, do not register properly there- 95 with. If now pressure be applied to force the rubber heel 10 toward the nailing die the rigid projections 38, entering the correspondingly shaped cavities 14, will force the yielding material of the heel 10 into such a 100 shape that the washers 20 will occupy accurately predetermined positions in line with the drivers 24. In the event that the holes 34 and 18 are in alinement when the parts are in the relative position illustrated in 105 Fig. 3, the projections 38, entering the cavities 14, simply serve to maintain the alinement, preventing any possible shifting of the washers by distortion of the heel due to the application of pressure. The nails 110 40 may now be deposited in the nailing die, for example, by the usual loader block 42, and will be guided positively and accurately all the way into the holes 18 of the heel 10 and, perforce, through the holes in 115 the centers of the washers 20. The drivers 24 are now caused to descend and drive the nails home, in which position, their heads are seated in the washers 20. This condition is illustrated in Fig. 4. The drivers 120 having been retracted and the pressure re- 125 moved, the shoe with the heel attached is ready to be taken from the machine.

In the course of the preceding description the term "rubber heel" has been used fre- 130

quently but it should be understood that this expression is to be construed in an inclusive sense rather than in a restrictive sense, it being intended to refer to any heel or heel lift or section made of yielding, elastic material having more or less of the characteristics of rubber.

Having thus described my invention, what I claim as new and desire to secure by Letters Patent of the United States is:—

1. A method of attaching elastic heels containing washers, consisting in first forcing the washers into predetermined, fixed, relative positions, and then driving heel attaching fastenings through the holes of the washers thus positioned.

2. A method of attaching elastic heels, consisting in preliminarily forcing those portions of a heel through which the attaching fastenings are to pass into predetermined, relative positions and then driving the fastenings through the heel while maintaining said portions of the heel in said positions.

3. A method of attaching elastic heels, containing washers, consisting in first forcing the washer containing portions of a heel into predetermined, relative positions, and then driving heel attaching fastenings through the holes of the washers.

4. A method of attaching elastic heels containing washers, consisting in first forcing the washers into predetermined, relative positions by engagement with portions of the heel adjacent to the washers, then driving heel attaching fastenings through the holes of the washers while maintaining them in said positions.

5. A method of attaching an elastic heel having cavities in its tread face, through which the attaching nails are to be driven, consisting in first positioning the cavities in predetermined, relative locations by engagement with their walls, and then holding them in said locations while the nails are driven.

6. A method of attaching an elastic heel containing washers and having cavities in its tread face in register with the washers, consisting in first forcing the washers into predetermined, relative positions by the engagement of the walls of the cavities with a positioning instrument, and then driving attaching nails through the washers.

7. Means for attaching elastic heels containing washers, comprising heel engaging instrumentalities constructed and arranged to force the washer bearing portions of a heel transversely into predetermined, relative positions.

8. Means for attaching elastic heels containing washers, comprising heel engaging instrumentalities, constructed and arranged to force the washer bearing portions of a

heel transversely into predetermined, relative positions and maintain them in said positions while the attaching nails are driven, and means for inserting and driving attaching fastenings through the portions of the heel thus positioned.

9. Means for attaching elastic heels comprising a pressure applying member constructed and arranged to engage the portions of a heel through which attaching nails are to be driven and shift them transversely into predetermined, relative positions.

10. Heel attaching mechanism for elastic heels comprising a pressure applying member having projections on its pressure applying face constructed and arranged to engage and shift the nail receiving portions of a heel transversely into predetermined, relative positions.

11. Heel attaching mechanism for elastic heels comprising a pressure applying member having fixed projections upon its pressure applying face constructed and arranged to engage certain portions of a heel and shift them transversely into predetermined, relative positions when said member and the heel are moved toward each other, means for effecting relative approaching movement of said member and heel, and means for driving attaching nails through said portions of the heel.

12. In a heel attaching machine for attaching heels having cavities in their tread faces, a nailing die having projections arranged to enter said cavities and position them in predetermined, relative locations, and nail guiding passages through said projections.

13. In a heel attaching machine for elastic heels containing washers and cavities in their tread faces in register with the washers, a pressure applying nailing die having predeterminedly arranged projections of the same size and shape as the cavities in a heel, nail guiding passages through the projections, and means for driving heel attaching nails through said passages into a heel held in engagement with the die.

14. Heel attaching mechanism for elastic heels comprising a nailing die having a heel engaging face conforming to a predetermined standard heel and provided with tapered projections to interlock with corresponding cavities in the washer bearing portions of the heel to preserve the relation of the washers in an accurate heel and to position the washers in an inaccurate heel to conform to the predetermined standard.

15. In a heel attaching machine for elastic heels containing washers and having cavities in their tread faces in register with the washers, a nailing die having predeterminedly arranged projections corresponding in shape to the cavities in a heel and the

remainder of the heel engaging portion of its face constructed and arranged to apply uniform pressure to all parts of the heel area except the cavities.

5. 16. In a heel attaching machine for elastic heels containing washers and having cavities in their tread faces in register with the washers, a nailing die having predeter-

minately arranged, tapered, projections corresponding to the cavities in a heel and the remainder of the heel engaging portion of its face flat and unbroken.

In testimony whereof I have signed my name to this specification.

SAMUEL STANICK.
